(57) **CLAIM**

The ornamental design for a canister for a reduced pressure treatment system, as shown and described.

DESCRIPTION

FIG. 1 is a top and right side perspective view of a canister for a reduced pressure treatment system showing our new design;

FIG. 2 is a top and left side perspective view thereof;

FIG. 3 is a top and rear perspective view of FIG. 1;

FIG. 4 is a top and rear perspective view of FIG. 2;

FIG. 5 is a top view thereof;

FIG. 6 is a bottom view thereof;

FIG. 7 is a right side view thereof;

FIG. 8 is a left side view thereof;

FIG. 9 is a right end view thereof; and,

FIG. 10 is a left end view thereof.

The broken lines illustrated in the drawings are for illustrative purposes only and form no part of the claimed design.
